5 Claims

ABSTRACT OF THE DISCLOSURE

A nonvibratory electric switch comprises a fixed contact element, a movable contact element in the form of a resilient leaf spring fixed at one end and engageable with the fixed contact element at its other end but normally in circuit-open position. A member for actuating the movable contact element to circuit-closing position is in the form of a fluid pressure-responsive device subject to vibration. A guide is interposed between the pressure-responsive device and the movable contact element and includes a guide surface in the form of a cylindrical bore extending therethrough. An actuating element in the form of a pin loosely fitting in the bore normally engages, but is movable independently of, the actuating member. A viscous fluid fills the space between the bore and the actuating pin and is effective to damp vibrations of the latter, whereby the switch contact elements are effectively isolated from vibratory movements of the actuating member.

BACKGROUND OF THE INVENTION

This invention relates to nonvibratory electric switches and particularly to such switches of the type adapted to be actuated by a fluid pressure-responsive device subject to vibration which, in the absence of the invention, causes the contacts to "chatter" when the device is set so that the range of control movement approaches the amplitude of vibration. The electric switch of the invention has been found particularly useful in precision control equipment that must operate within close pressure bands under severe vibration.

A conventional prior fluid pressure-responsive electric switch has comprised a fixed contact element and a movable contact element either secured to, or actuated directly by, the pressure-responsive device, usually in the form of a pressure capsule, bellows, diaphragm, or the like. If it is desired to actuate the switch in response to relatively small changes in pressure and if the device is subject to vibration, it frequently occurs that the range of control movement of the actuating pressure-responsive device becomes of the same order as the amplitude of its vibratory movement, causing the switch contacts to chatter, that is, to open and close at the vibratory frequency.

SUMMARY OF THE INVENTION

In accordance with the invention, there is provided a nonvibratory electric switch comprising a fixed contact element, a movable contact element including a resilient member normally holding the same in a predetermined relation to the fixed element, and a member for actuating the movable element to a different relation to the fixed element, such member being subject to vibration. The electric switch of the invention also comprises a guide interposed between the actuating member and the movable element and including a cylindrical bore extending therethrough and a pin disposed in the bore with a clearance of the order of 0.0003 inch and normally engaging the actuating member. A fluid having a viscosity of the order

2

of 5000 cs. fills the space between the cylindrical bore and the pin and is effective to damp vibrations of the latter, whereby the contact elements are effectively isolated from vibratory movements of the actuating member.

For a better understanding of the present invention, together with other and further objects thereof, reference is had to the following description, taken in connection with the accompanying drawing, while its scope will be pointed out in the appended claims.

10 BRIEF DESCRIPTION OF THE DRAWING

In the drawing:

FIG. 1 is a cross-sectional view of a nonvibratory electric switch embodying the invention;

FIG. 2 is a diagrammatic representation of the operation of a prior art switch of the type described, while

FIG. 3 is a similar diagram representing operation of an electric switch embodying the present invention.

20 DESCRIPTION OF THE PREFERRED EMBODIMENT

Referring now to FIG. 1 of the drawing, there is represented in cross-section a nonvibratory electric switch comprising a cup-shaped housing 10, the open end of which is closed by a threaded plate 11 engaging internal threads 10a of the housing 10. Mounted in the plate 11 is a fixed contact element 12 secured to a terminal 13. A movable contact element is in the form of a resilient leaf spring 14 fixed at one end to a terminal 15 and the other end being engageable with the fixed contact element 12, the contact elements 12 and 14 being normally open, as shown.

The electric switch of the invention further comprises a member for actuating the movable element 14 to a different relation to the fixed element 12, specifically to circuit-closing position. The actuating member is shown in the form of a fluid pressure-responsive device, specifically a bellows 16 having a fluid connection through a port 17 extending through the lower wall of the housing 10. A guide is interposed between the actuating bellows 16 and the movable contact element 14 in the form of a bushing 18 secured to or integral with the plate 11 and including a guide surface in the form of a cylindrical bore through the bushing 18. In the bore of the guide 40 18 is disposed an actuating element in the form of a loosely fitting pin 19. The pin 19 normally engages the upper face of the bellows 16 but merely rests thereon so that it is freely disengageable therefrom.

In the electric switch of the invention, the space between the guide surface or bore in the bushing 18 and the actuating pin 19 is filled with a viscous fluid which is retained solely by capillary attraction. This viscous fluid is effective to damp vibrations of the actuating pin 19, whereby the contacts 12, 14 are effectively isolated from vibratory movements of the actuating bellows 16.

The operation of the electric switch of the invention in comparison with conventional prior electric switches of a similar type is shown in FIGS. 2 and 3. In FIG. 2, the upper face of the bellows 16 is shown as partaking of a sinusoidal vibratory movement, represented by curve A. In its uppermost position, the bellows, acting through the conventional pin, close the switch contacts as shown. In the lowermost phase of its vibratory movement, the bellows cause the pin to retract with the bellows, either by being secured to the bellows or by falling of its own weight, thereby permitting the switch contacts to open, as illustrated. This cycle is repeated, as shown in the two succeeding maximum and minimum of the vibratory curve A. The pin is shown as sliding in a guide merely to restrict its lateral movement.

Turning now to FIG. 3, it is assumed that the bellows still partake of the same sinusoidal vibratory movement

represented by curve A. In this instance however, the actuating pin is damped by the viscosity of the oil filling the space between the bore of the bushing 18 and the pin so that, when the bellows reach their minimum position on curve A, the pin is restrained from downward movement, maintaining the contacts closed. This cycle is repeated, as shown with respect to the two succeeding phases of the sinusoidal curve A.

It has been found that the clearance between the pin 19 and the bore of the bushing 18 may be of the order of 0.0003 inch and that the viscosity of the fluid may have a value of the order of 5000 cs. In one embodiment of the invention which has proved satisfactory, the clearance between the pin 19 and the bore of the bushing 18 was of the order of 0.0003 inch and the fluid was silicone oil having a viscosity value of the order of 5000 cs. In the embodiment of the invention described, the range of amplitude vibration was up to ± 0.20 inch and the range of vibration frequencies effectively damped by the construction described was from 5 to 2000 cycles per second.

While there has been described what is, at present, considered to be the preferred embodiment of the invention, it will be obvious to those skilled in the art that various changes and modifications may be made therein, without departing from the invention, and it is, therefore, aimed in the appended claims to cover all such changes and modifications as fall within the true spirit and scope of the invention.

What is claimed is:

1. A nonvibratory electric switch comprising:
a fixed contact element;
a movable contact element including a resilient member normally holding the same in a predetermined relation to said fixed element;
a member for actuating said movable element to a different relation to said fixed element, said member being subject to vibration;
a guide interposed between said actuating member and said movable element and including a cylindrical bore extending therethrough;

a pin disposed in said bore with a clearance of the order of 0.0003 inch and normally engaging said member;
and a fluid having a viscosity of the order of 5000 cs. filling the space between said cylindrical bore and said pin effective to damp vibrations of the latter, whereby said contact elements are effectively isolated from vibratory movements of said actuating member is effective to close the same.

5 2. A nonvibratory electric switch in accordance with claim 1 in which said contact elements are normally open and said actuating member is effective to close the same.

10 3. A nonvibratory electric switch in accordance with claim 1 in which said resilient member is in the form of a leaf spring fixed at one end and engageable with said fixed contact element at its other end.

15 4. A nonvibratory electric switch in accordance with claim 1 in which said actuating member is a fluid pressure-responsive device.

20 5. A nonvibratory electric switch in accordance with claim 1 in which the viscous fluid is a silicon oil.
